UNITED STATES PATENT OFFICE.

THOMAS R. BROWN, OF SPARKILL, NEW YORK, ASSIGNOR TO THE WESTINGHOUSE AIR BRAKE COMPANY, OF WILMERDING, PENNSYLVANIA, A CORPORATION OF PENNSYLVANIA.

AUTOMATIC TRAIN-PIPE COUPLING.

1,263,519.

Specification of Letters Patent. Patented Apr. 23, 1918.

Application filed October 11, 1913. Serial No. 794,614.

To all whom it may concern:

Be it known that I, THOMAS R. BROWN, a citizen of the United States, residing at Sparkill, in the county of Rockland and 5 State of New York, have invented a certain new and useful Improvement in Automatic Train-Pipe Couplings, of which improvement the following is a specification.

This invention relates to automatic train 10 pipe couplings of the type having a valve mounted in the train pipe passage for controlling the flow of fluid, and adapted to be opened automatically when the two counterpart couplings are brought together in 15 the act of coupling, and to be closed and prevent the escape of fluid when the coupling members are separated in uncoupling the cars or other vehicles. The principal object of my invention is to provide an improved 20 coupling device of this character in which the valve may be automatically closed to prevent the escape of train pipe fluid when it is desired to separate the cars and at the time that the coupler is operated to release 25 or uncouple the same, but will be held open to permit the discharge of a sufficient quantity of train pipe fluid to cause the automatic application of the brakes in the usual manner, when the cars are accidentally pulled 30 apart as in the case of a break-in-two of the train.

While my improvement is adapted to be supported between the cars by any suitable or preferred means, I have herein illustrated 35 the same as applied in connection with a coupler of the closed or rigid lock type in which the train pipe passage and coupling is carried directly by and through the car coupler, as shown in the accompanying 40 drawings, in which Figure 1 is a horizontal section of one form of coupler embodying my improvement; and Fig. 2, a horizontal section of the two couplers coupled together, the rear portions being broken away.

According to the construction shown in 45 the drawings, the coupler head, 12, is adapted to be pivotally connected to the drawbar, and is provided with the projecting end portion, 14, arranged to engage the corresponding portion of the counterpart coupling by a lateral movement along a longitudinally inclined vertical plane, and then 50 be rigidly locked together in such position by the cam lever, 16, bearing upon the face, 55 17, of the projection, 14. The locking lever

may be operated by any suitable means, such as the rod, 19, connected to the piston, 18, subject on one side to the spring, 20, normally holding the lever, 16, in locking position, but adapted to be released by admitting fluid pressure through the passages, 22 and 23, to the cylinder on the other side of the piston.

The train pipe section having passage, 24, is mounted directly upon the coupler head, 65 12, and the forward end of the train pipe opening is provided with a gasket, 25, adapted to engage the corresponding gasket on the other coupling, and make a fluid tight joint when the parts are coupled together. 70 In the train pipe passage is mounted the valve, 26, having a stem, 28, extending out through the open end of the gasket, and adapted to engage the corresponding stem on the other coupler member and raise both 75 valves from their seats when the couplers are brought together. The valves are normally closed by springs, 27, when the couplers are separated.

As thus far described, the construction is 80 substantially the same as that covered in the prior application of Doyle and Hedley, filed March 24, 1913, Serial No. 756,469.

For the purpose of holding the valve open 85 temporarily in case the couplers are accidentally pulled apart, I provide a piston, 30, connected by a stem, 29, to the valve, 26, the piston operating in a cylinder in open communication with the train pipe line on one side through the port or passage, 31, while 90 the release of fluid pressure from the cylinder on the opposite side of the piston is controlled by a manually governed valve which is opened at the time it is desired to release and separate the couplers, but is closed when 95 the parts are coupled together.

This valve may be a small independent cock, 34^a, as indicated in Fig. 2, which may be opened by hand to release fluid from one side of the piston through passage, 32, or 100 may be a valve, 34, operated by the plunger, 35, when fluid is admitted to the space, 22, port, 23, and the cylinder of piston, 18, as shown in Fig. 1, for releasing the coupler.

When the parts are coupled together, the 105 valves, 26, are automatically opened by the abutting stems, 28, the ports, 32, are closed, and fluid pressure from the train pipe communicates freely through the port, 31, in stem, 29, with the chamber at one side of the 110

piston, 30. As the piston, 30, fits rather loosely in its cylinder, the fluid pressure immediately equalizes around the same into the chamber on the opposite side, and the piston thus remains normally balanced as to fluid pressure. If then the coupling members should be accidentally pulled apart, it will be seen that the valves, 26, of the couplers would remain open temporarily until the pressure at the inner side of the piston, 30, leaks away sufficiently to permit the slow closing of the valve. This will allow a sufficient amount of compressed fluid to escape from the open ends of the train pipe to produce the usual automatic application of the train brakes.

When, however, it is desired to uncouple and separate the cars, the small valve, 34, or 34^a, controlling the port, 32, is opened, thereby releasing the fluid from the chamber at the inner side of piston, 30, and thus causing the instant closing of the valve, 26, by means of the train pipe pressure and the spring acting on the other side as soon as couplings are separated. This prevents the undesired discharge and waste of compressed air from the train-pipe.

Where my improvement is employed in connection with the type of coupler shown in Fig. 1, in which the coupler lock is operated by fluid pressure, the same manual control which admits fluid pressure to release the lock also effects the opening of the vent valve, 34, by the movement of plunger, 35, and thereby releases fluid from the passage, 32, through exhaust port, 36, to the atmosphere. Where my improved train pipe coupling is supported in other ways, the cock, 34^a, may be operated independently or may be operated by any desired form of coupler releasing mechanism.

Having now described my invention, what I claim as new and desire to secure by Letters Patent is:—

1. In a coupling, the combination with a coupler head having a train pipe passage with an opening adapted to register with a

corresponding opening in a counterpart coupler, of a movable coupler lock, a fluid pressure operated device for releasing said lock, 50 a valve for controlling said passage, a piston attached to said valve, and means operated by the fluid pressure supplied to said releasing device for controlling the pressure acting on said piston. 55

2. In a train pipe coupling, the combination with a coupler head having a train pipe passage with an opening adapted to register with a corresponding opening in a counterpart coupling, of an automatic valve 60 mounted in said passage, a piston subject to fluid pressure and having a stem rigidly connected to said valve, and means for controlling the pressure on one side of said piston and thereby govern the closing movement of 65 the valve.

3. In a train pipe coupling, the combination with a coupler head having a train pipe passage with an opening adapted to register with a corresponding opening in a counterpart coupling, of an automatic valve mounted in said passage, a piston rigidly connected to said valve and subject on its opposite sides to fluid pressure, and a valve for controlling the release of fluid from one side of 75 said piston.

4. In a train pipe coupling, the combination with a coupler head having a train pipe passage with an opening adapted to register with a corresponding opening in a counterpart coupling, of an automatic valve mounted in said passage, and having a stem projecting through said opening, a spring tending to close said valve, a piston, subject on one side to fluid pressure, tending to hold 85 said valve open, and means for controlling the release of fluid from said piston.

In testimony whereof I have hereunto set my hand.

THOMAS R. BROWN.
